DISPENSING SPOUT AND CLOSURE WITH
ADJUSTABLE SIFTER

Philip Brooks, Darien, Conn., assignor to International Salt Company, Scranton, Pa.

Application October 4, 1949, Serial No. 119,413

5 Claims. (Cl. 222—189)

1

This invention relates to container dispenser means, and more particularly to an improved spout device for containers of granular materials such as salt, sugar and the like, whereby the container contents may be selectively poured or sprinkled in improved manner therefrom.

One of the objects of the invention is to provide an improved closure and dispensing spout of the character referred to whereby the container contents may be either poured or sprinkled through said spout in improved manner.

Another object of this invention is to provide an improved spout device of the character described which is adapted to selective operation for either pouring or sifting or spraying the container contents therethrough in improved manner.

Still another object of the invention is to provide a spout device of the character described which is constructed to provide an improved type of sprinkling action.

Still another object of the invention is to provide a combination closure and pouring-sifting spout device of the character described which is adapted to be manually adjusted between fully closed and pouring and spraying and sprinkling positions with utmost ease and facility.

Still another object of the invention is to provide a device of the character described which is adapted to be manufactured inexpensively, and which is simple and rugged in construction.

Other objects and advantages of the invention will appear from the specification hereinafter.

In the drawing:

Fig. 1 is a perspective view of a container fitted with a closure-spout device of the present invention;

Fig. 2 is a fragmentary perspective thereof, on an enlarged scale, showing the spout device adjusted to sprinkling condition; and

Fig. 3 is a fragmentary section, taken on a larger scale, taken along line III—III of Fig. 2.

The invention is illustrated by way of example in conjunction with a container designated 10 which is illustrated to be of the presently popular paperboard cylindrical type container, such as in which household or table salt is packaged. However, it is to be understood that the container per se may be of any other shape, style, or construction, such as a rectangular shape; but in any event will be formed to include a wall portion 12 which is apertured as indicated at 14 to permit dispensing of the container contents therethrough.

The spout means of the invention comprises a

5 two-part device consisting of a combination closure and spout element 16 which is constructed of sheet metal, plastic, paperboard or any other material, to comprise a bottom plate portion 18 and a pair of segmentally shaped side wall portions 19—19; the bottom plate portion 18 being formed at its inner end with a hinge eye 20 and at its outer end with a finger tab 21. The eye portion 20 is arranged to receive a hinge pin 22, which is positioned upon the container by any suitable means, such as by a stapling procedure as indicated at 24. Thus, the spout member 16 is pivotally mounted upon the container so as to be rotatable thereon between dispenser closed position and pouring position; the side walls 19—19 of the spout member being formed with laterally turned ear portions 26 (Fig. 2) for limiting outward pivoting movement of the spout member to the pouring position thereof.

10 The second element of the spout device of the invention comprises a novel screen member 30 which is in the form of a smoothly curved metal strip perforated at intervals as indicated at 32 and formed with a finger tab portion 33 and a side wall portion 34 which in turn includes a bottom flange 35 terminating in an eye 36 which pivotally engages upon the hinge pin 22. The screen plate 30 is curved to align with the outer marginal contours of the spout side walls 19—19 which are concentric with the hinge pin 22. Also, the perforated plate member 30 terminates at its inner end in an up-turned flange portion 38 (Fig. 2) which is adapted to function as a stop device to prevent outward swinging of the screen member 30 beyond the position thereof shown in Fig. 2.

15 Thus, it will be appreciated that the members 16 and 30 are selectively pivotable upon the hinge pin 22, by simple manual manipulations of the finger tab portions 21—33 thereof; and that whenever both members are pushed toward closed positions the container dispensing aperture is thereby closed off. Then, for example, upon pulling upon the finger tab 21 the pouring spout member 16 may be thereby swung outwardly so as to provide a trough in open communication with the dispensing aperture 14 of the container through which the salt or other contents of the container may be poured in the form of a solid stream. Or, if it is desired to sprinkle the contents of the container, the finger tab 33 is also pulled upon so as to draw the screen member 30 outwardly into position whereby the finger tab portions 21—33 snugly lap; whereupon the salt or other contents of the container will flow through 20 the container aperture 14 and thence through

the spout member 16 and thence out of the perforations 32 of the screen member 30.

Thus, it will be appreciated that the container contents may be sprinkled in an improved guided manner, directly from the outwardly extending screen plate 30, which is kept fully loaded during such sprinkling operations by reason of the free path for the commodity to be dispensed through the open spout to the rear face of the screen plate. Also, it will be appreciated that whenever the screen plate 30 is pivoted to its retracted position it avoids interference with the normal spout pouring operation; and that when the spout member is pushed to "closed" position it automatically displaces the screen member to inoperative position and seals the container.

Still another form of dispensing operation is available in accord with the invention, by simply positioning the finger tab members 21-33 to be slightly apart; thereby providing an open "lips" effect between which the salt or other commodity may issue in the form of a substantially flat spray. Thus, shaking of the container in a laterally oscillating manner will result in still another form of commodity spreading action as illustrated for example at 40 in Fig. 2; and it will of course be understood that the members 16-30 may be snugly fitted upon the hinge pin and in the container wall aperture so that they are frictionally resistant to movement, whereby they will remain in any adjusted position. Or, any other suitable detent means or the like may be employed if preferred to cause the members to remain in their adjusted closed or open or partially open positions.

Thus, it will be appreciated that the dispenser of the invention provides for optional dispensing of material in the form of a full pouring or a sifted sprinkling or a flat spray; and although only one form of the invention has been shown and described in detail, it will be understood that various changes may be made therein without departing from the spirit of the invention and the scope of the appended claims.

I claim:

1. A combination closure and commodity dispensing device adapted to be mounted upon an apertured wall portion of a container for selective dispensing of granular commodity therefrom, said dispensing device comprising in combination a hinge pin fixed to the container wall adjacent the apertured portion thereof, a spout device comprising a trough shaped member having a bottom wall and a pair of opposite side walls extending therefrom, said bottom wall having an eye portion formed at one end for pivotal engagement with said hinge pin and formed at its other end with an extending finger tab, said side wall portions being segmental shaped and formed with outwardly directed flange portions adjacent their inner ends for abutting contact with the interior of said container wall whereby said spout device is pivotable between extended and retracted positions relative to said container wall within the limits of movement permitted by said stop devices, and a screen device slip-fitted within said spout device and comprising a perforate top wall portion aligned with the open top portion of said spout device and a side wall portion extending alongside one of the side wall portions of said spout member and terminating in an eye engaging said hinge pin whereby said screen device is pivotable within said spout device between positions providing covering and uncovering of the open top portion of said spout

device, said screen device being formed with an outstanding flange at the inner end thereof for abutting engagement against the inner surface of said container wall, whereby said spout and screen devices are selectively pivotable upon said hinge pin device between extended and retracted positions relative to the container.

2. A combination closure and commodity dispensing device adapted to be mounted upon an apertured wall portion of a container for controlling dispensing of discrete material therefrom, said dispensing device comprising in combination a hinge pin adapted to be fixed to the container wall adjacent the apertured portion thereof, a spout device comprising a sheet member bent to U-shaped sectional form and having a bottom wall and a pair of segmental shaped, opposite side walls extending therefrom, said bottom wall having an eye portion formed at one end for pivotal engagement with said hinge pin, one of said side wall portions being formed with an outwardly directed flange for abutting contact with the interior of said container wall whereby said spout device is pivotable between extended and retracted positions relative to said container wall within the limits of movement permitted by said stop device for pouring type dispensing, and a screen device slip-fitted within said spout device and comprising a perforate top wall portion aligned with the outer marginal portions of said spout device side walls and a side wall portion extending alongside one of the side wall portions of said spout member and terminating in an eye portion engaging said hinge pin whereby said screen device is pivotable within said spout device between positions providing covering and uncovering of the discharge opening portion of said spout device to provide for sprinkling of the material from the end of said spout when desired, whereby said spout and screen device are selectively pivotable upon said hinge pin device between extended and retracted positions relative to the container.

3. A dispensing closure device for mounting upon a container aperture for selective dispensing of powdered or granular material therefrom, said device comprising a spout member of trough shaped form having a bottom wall and opposite side walls extending therefrom, said bottom wall having means formed at one end thereof for pivotal engagement with the container at an edge of the apertured portion thereof and formed at its other end with an extending finger tab, stop means for limiting pivoting movement of said spout member when mounted upon the container whereby said spout member is pivotable between extended and retracted positions relative to said container within the limits of movement permitted by said stop means, and a screen member slidably between said side walls along the outer marginal portions thereof to span the space therebetween and bridge the dispensing outlet of said spout member, whereby said screen member is movable within said spout member between positions providing alternately for free passage and screening of material passing through said spout member.

4. A dispensing closure device adapted to be mounted upon an apertured portion of a container for controlling dispensing of pourable material therefrom, said device comprising a spout member of generally U-shaped form having a pair of opposite side walls, means pivotally mounting said spout member upon said container so as to be pivotable between extended and re-

tracted positions relative to said container, and a screen member of generally arcuate form in lengthwise extent inverted relative to said spout member and slideable within said spout member between positions providing either free passage or screening of material pouring through said spout member, whereby said spout and screen members are selectively movable between extended and retracted positions relative to the container.

5. A combination container closure and commodity dispensing device adapted to be mounted upon an apertured wall portion of a container for controlling dispensing of material therefrom, said dispensing device comprising a trough-shaped spout member having opposed side walls and formed at one end for engagement with said container, said spout member being formed with stop means whereby said spout member is movable between extended and retracted positions relative to said container wall within the limits of movement permitted by said stop means, and

a screen member movable relative to said spout member along the outer marginal portions of said side walls between positions providing screen covering and uncovering of the discharge portion of said spout member, whereby said spout member is movable between extended and retracted positions relative to the container and said screen member is independently movable between screening and open positions relative to the discharge end portion of said spout member.
